US0D1082825S

(12) **United States Design Patent** (10) Patent No.: **US D1,082,825 S**
(45) Date of Patent: ** Jul. 8, 2025

(54) **DISPLAY SCREEN WITH GRAPHICAL USER INTERFACE**

(71) Applicant: **Airbnb, Inc.**, San Francisco, CA (US)

(72) Inventors: **Brendan Pascoe**, San Rafael, CA (US);
Douglas Alves, Palo Alto, CA (US);
Sayaka Sugimura, South Pasadena, CA (US); **Mark Dennis Laughlin, Jr.**, Santa Cruz, CA (US)

(73) Assignee: **Airbnb, Inc.**, San Francisco, CA (US)

(**) Term: **15 Years**

(21) Appl. No.: **29/914,017**

(22) Filed: **Oct. 11, 2023**

(51) LOC (15) Cl. **14-04**

(52) U.S. Cl.

USPC **D14/492**

(57) **CLAIM**

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and forms no part of the claimed design. The remaining broken lines within the peripheral dash-dot-dash lines illustrate portions of the graphical user interface which form no part of the claimed design.

1 Claim, 1 Drawing Sheet
